BOILER

Paul Augustin-Normand, Le Havre, France, assignor to Société Anonyme Chantiers et Ateliers Augustin Normand, Le Havre, France

Application April 27, 1931, Serial No. 533,330,
and in France February 16, 1931

5 Claims. (Cl. 122—236)

The present invention relates to new arrangements of express water-tube boilers with one upper steam and water drum and one lower water drum, comprising two combustion chambers, which are bounded on one side by the main heating surface, heated chiefly by convection and located almost vertically so as to further the circulation, and which are wholly surrounded on the other side by evaporating tubes outwardly curved and heated solely by radiation so as to prevent the loss of the heat radiating laterally and towards the lower part of the boiler.

The arrangements proposed by the present invention also propose the possible use of superheater nests of tubes located among the evaporating tubes constituting the main heating surface at suitable places which depend upon the amount of superheat which it is wished to obtain. Suitable baffles allow of directing the path of the gases if this be necessary so that said gases may follow a predetermined path, which however can vary according to the proposed arrangements. Thus it is possible to propose a single or double longitudinal circulation with frame-return, or a vertical circulation. The baffles can be constituted only by tubes, which then are touching, or in any other way.

The accompanying drawings show by way of example three constructions according to the invention.

Fig. 1 shows a section of the nest of tubes of a boiler made at right angles to the axes of the drums.

Fig. 2 is a section on the line A—A of Fig. 1 and shows that the gases follow a single longitudinal path.

Fig. 3 is another section on the line A—A of Fig. 1 and shows that the gases follow a double longitudinal path instead of following a single longitudinal path as in the case of Fig. 2.

Fig. 4 is a half-section corresponding to the case in which a vertical path for the gases is adopted.

Fig. 5 is similar to Fig. 4 but shows a small longitudinal sheet-iron baffle arranged in the top of the principal nest.

Fig. 6 shows a hollow brickwork,

Fig. 7 shows a brickwork provided inside with water tubes.

Fig. 8 shows a brickwork protected on its inner face with water tubes; and

Fig. 9 shows a mechanical device for intensifying the circulation of water.

In the arrangement which is shown in Fig. 1, all the evaporating tubes connect an upper steam

and water drum 1 to a lower water drum 2; the greater part of these tubes constitutes the central nest 3, which are arranged in spaced vertical columns and traversed by the hot gases, whilst some tubes 4 bound the combustion chambers 60 externally over the remainder of their circuit, these tubes being heated by radiation alone and preventing, as already stated, the loss of heat not only laterally but also by the lower part of the boiler. A superheater nest of tubes 5 can be 65 inserted vertically between the columns of the central nest between two lower and upper steam drums 6 and 7. The gases can follow a longitudinal path either single or double and, in the case of the double longitudinal path, the size of section 70 to be given respectively to the two parts of the central nest of evaporating and superheating tubes, that is to say to the parts traversed by the gases in different directions, should be calculated in such way as to allow for the normal 75 flow, through the second part, of the bulk of the gases which has traversed the first part, taking into account the decrease in volume of this bulk owing to its cooling. The first part of the central nest can then be constituted by the evaporating 80 tubes 3, whilst the second part can be constituted, either on its whole length or on part of its length, by the superheater tubes 5. It is scarcely necessary to state that, with equal intensity of combustion, the single longitudinal path will ensure 85 a greater superheating than the double longitudinal path.

In the case of Fig. 2 the gases follow a single longitudinal path, as shown by the arrows in Fig. 2, and this path is obtained by means of baffles 9 90 consisting of the touching tubes of the central nest 3.

In the case of Fig. 3, the gases follow a double longitudinal path indicated by arrows, this path being obtained by means of baffles 9 and 10 consisting of the touching tubes of the nest 3, the baffles 9 separating the combustion chambers from the first parts of the central nest and being located to the front, whilst the baffles 10 separate the first parts of the central nest from the second 100 part and are located only to the back.

In the case of Figs. 2 and 3, the external row of the peripheral nest has been shown touching, the better to protect the shell from radiation from the furnace.

In the arrangement shown in Fig. 4, the evaporating tubes all connect the upper steam and water chamber 1 to the lower water vessel 2, as in the case of Fig. 1, but the gases are constrained to follow a transverse path, the gases 110

entering the central nest at the lower part and leaving it at the upper part. The combustion chamber and the central heating surface are separated in the upper region by a baffle of 5 touching tubes so that the hot gases cannot pass directly from the combustion chamber to the smoke-box, and must follow the path indicated by the arrows in Fig. 4. A small longitudinal packing of sheet-iron, asbestos or any arrangement of fire proof material 12 (Fig. 5) can moreover be arranged in the top of the principal nest, where it meets each of the peripheral nests, so as to prevent the gases from passing through the gaps between the tubes, which there no longer 10 touch each other.

In the case of Fig. 4, it is assumed that a superheater 11 with horizontal tubes is located in each half of the central nest.

The arrangement of a small additional water 20 drum 8, as shown in Fig. 5, might be adapted to all the arrangements here suggested for the purpose of decreasing the length of the tubes constituting the two nests heated solely by radiation.

25 It is to be clearly understood that the examples of construction described above and shown in the accompanying drawings are not of a limiting character and that various modifications may be introduced without exceeding the scope of the 30 invention. More particularly, the shape of the superheater may be different. The baffles which direct the path of the gases, instead of being constituted by touching tubes forming part of an evaporating nest, may be constituted by an 35 assemblage of tubes and blocks or plates of metal, by an assemblage of tubes and brickwork, by brickwork alone or finally by sheets or plates of refractory or inoxidizable materials; each time that a baffle is provided at the side of the furnace, 40 it may be built, either at the first row of the nest or at a row further back towards the interior of this nest (for example the second or third) if it be wished to expose a bigger heating surface to the radiant heat.

45 Instead of being plain, the brickwork 15 at the ends may be hollow (Fig. 6), or provided inside

with water tubes 13 (Fig. 7), or protected by same 14 (Figs. 5 and 8). The boiler arrangements proposed are adapted for a double-ended arrangement, that is to say, in which two identical boilers are connected together by their back ends. It is to be noted that the arrangements proposed are equally applicable to firing with ordinary coal, with pulverized coal or with liquid or gaseous fuel.

It is obvious that all the boilers of which the arrangement of the nests of tubes has been stated may be furnished with downcomer tubes 16 outside the furnace and that the circulation in these tubes may be intensified by means of mechanical devices 17 (Fig. 9), and, on the other hand, all these boilers may be completed by the addition of feed water heaters and air-heaters.

What is claimed,

1. An express water-tube boiler comprising a single upper drum, a single receiver drum, a main heating surface in the form of tubes arranged between the drums and positioned in a substantial vertical direction, two combustion chambers arranged on opposite sides of the main heating surface, auxiliary heating surfaces consisting of a single range of tubes surrounding the outer sides of the two combustion chambers and heated only by radiation and means for conducting the heating gases from the two combustion chambers through the main heating surface substantially in all parts of said main heating surface.

2. An express water-tube boiler as claimed in claim 1, wherein means are provided to cause the gases to follow a single path.

3. An express water-tube boiler as claimed in claim 1, wherein means is provided to cause the gases to follow a double path.

4. An express water-tube boiler as claimed in claim 1, wherein the tubes of the main heating surface are arranged in spaced vertical columns, and superheater tubes arranged vertically between the columns.

5. A boiler as claimed in claim 1, wherein a small drum is interposed in the single range of tubes forming the auxiliary heating surfaces.
